UNITED STATES PATENT OFFICE

120,271

DESIGN FOR A GLASS BOTTLE

John H. Meier, Jr., Pittsburgh, Pa., assignor to
J. T. & A. Hamilton Company, a corporation of Pennsylvania

Application February 20, 1940, Serial No. 90,378

Term of patent 14 years

To all whom it may concern:

Be it known that I, John H. Meier, Jr., a citizen of the United States, residing in Pittsburgh, in the county of Allegheny and State of Pennsylvania, having invented a new, original, and ornamental Design for a Glass Bottle, of which the following is a specification, reference being had to the accompanying drawing, forming part thereof.

The figure is an elevational view of a glass bottle showing my new design. The bottle is, throughout its height, circular in horizontal section, and the ornamentation is uniformly continued throughout the periphery of the bottle.

I claim:

The ornamental design for a glass bottle, substantially as shown and described.

JOHN H. MEIER, JR.
